UNITED STATES PATENT OFFICE.

JAMES DAVIES, OF MITCHELL, ASSIGNOR OF ONE-HALF TO FRED. M. PRATT,
OF WHITE LAKE, DAKOTA TERRITORY.

VENTILATING-COVER FOR MILK-PANS.

SPECIFICATION forming part of Letters Patent No. 337,816, dated March 16, 1886.

Application filed December 14, 1885. Serial No. 185,681. (No model.)

To all whom it may concern:

Be it known that I, JAMES DAVIES, a citizen of the United States, residing at Mitchell, in the county of Davison, Dakota Territory, have 5 invented a new and useful Improvement in Ventilating-Covers for Milk-Pans, of which the following is a specification, reference being had to the accompanying drawings.

This invention relates to ventilating-covers 10 for milk-pans, pails, cans, and other open vessels, and has for its object to provide a device of this character which shall exclude insects and flying foreign substances of every description from the vessel, and at the same time allow a 15 free circulation of air over the surface of the milk, and also prevent the water which condenses on the inner surface of the cover from falling back into the milk.

With these objects in view the said invention 20 consists in the peculiar construction and combination of parts, as will be hereinafter set forth, and particularly pointed out in the claims.

In the accompanying drawings, Figure 1 is 25 a side elevation of a milk-pan with my improved cover fitted in position thereon. Fig. 2 is a similar view illustrating the attachment of my cover to a milk-can. Fig. 3 is a longitudinal section taken centrally through Fig. 30 1. Fig. 4 is a detached side elevation of a portion of the perforated wall. Fig. 5 is a detail view illustrating a modification.

Like letters are used to indicate corresponding parts of the several figures.

Referring to the drawings, it will be seen 35 that my ventilating-cover comprises, essentially, a sloping top, A, a depending circular wall, B, and a horizontal base or rim, C. These parts are constructed of three separate pieces 40 of tin or other sheet metal, the wall B having its upper and lower edges soldered or otherwise secured to the top A and the base or rim C. The wall B is secured to the top some distance inward from its outer edge, so as to 45 form a projecting flange, a, on the top, which will extend beyond the wall, so that should any water find its way on the top A it will be prevented from obtaining access to the interior of the vessel through the perforated wall 50 B, since the flange a serves to carry off the water beyond the latter. The wall B may be made

entirely of perforated sheet metal, or, as shown in the drawings, of imperforate metal having holes cut through the same at suitable intervals, as at b, these holes being covered with 55 wire-gauze or other open-work material, either construction effecting the desired end by securing a proper degree of ventilation, though for practical purposes I prefer the construction shown in the drawings. At the point of connection with the top A and base or rim C, the wall B is notched or cut out at regular intervals, as at E, to form openings when the wall is secured in position, these openings E permitting the passage of the water which condenses on the inner surface of the sloping top A, and thus preventing it from falling back 60 into the milk. The lower edge of the wall B is secured at some distance inward from the outer edge of the rim C, so as to leave the projecting flange e on the rim, as will be seen. This rim C, which forms the base of the cover, has on its under side, a short distance inward from the point of connection with the wall B, an annular groove or depression, F, which is 65 adapted to receive the upper beaded edge of the pail or can D, and thus support the cover in position on the pail and prevent lateral displacement. In lieu of this connection between the milk pail or can and the rim or base C of 70 the cover, I may secure by solder or otherwise on the outer face of the rim C a U-shaped piece of tin, (shown at the point G, Fig. 5,) the beaded upper edge of the pail fitting within the strip G between its side walls and holding 75 the cover thereon. It will be understood in both cases—i. e., whether a groove, F, is formed in the base or rim or a strip, G, attached thereto—two parallel guide-walls are provided, in the space between which walls the upper 80 beaded edge of the vessel is received. This arrangement allows the ready detachment of the cover and its insertion on the vessel without any catches or other complicated fastening means. The rim or base C extends inwardly 85 from the groove or depression F a short distance over the top of the pail or can, leaving an opening in the center of the base or rim for the passage of the cold air entering through the perforated wall B. The peculiar curved 90 or sloping top A, combined with the construction of the perforated wall B, having the open-

- ing E, enables the moisture condensing on the inner surface of the top A to be carried off to each side and escape through the top openings at the junction of the wall B with the top A.
5. Should any of the moisture escape beyond these openings down the inner surface of the wall B onto the rim or base C, this moisture would be carried out through the lower openings, E, at the base C, as will be seen.
- o In the use of this improved cover I do not wish to be confined exclusively to vessels for containing milk, as it may be used for covering any other material requiring ventilation. The inner end of the rim C is turned up or flanged, as shown in Figs. 3 and 5, so as to prevent the water of condensation, should any reach the rim, from dropping down into the milk.
- Having described my invention, I claim—
1. In a ventilating-cover, the solid top A, provided with the ventilating-wall B, depending therefrom, and the horizontal base or rim C, projecting inwardly from its point of connection with the wall and resting on the upper edge of the vessel to support the cover, as set forth.
2. In a ventilating-cover, the top A, having a flange, a, and provided with the wall B, having ventilating-openings, and the base or rim C, as set forth.
3. A ventilating-cover having the sloping top A, and the wall B, provided with escape-openings E at the point of connection with the top, as set forth.

4. A ventilating cover having the top A, 35 the wall B, provided with escape-openings E at the point of connection with the top, and the base or rim C, as set forth.

5. A ventilating-cover having the top A, 40 the wall B, depending therefrom and provided with ventilating-openings, and the base or rim C, connected to the wall and extending inwardly therefrom, so as to rest upon the upper edge of the vessel and support the cover, the wall of the cover being held away from the 45 vessel, as set forth.

6. A ventilating-cover having the top A, 45 the wall B, depending therefrom and provided with ventilating-openings, and the base or rim C, connected to the wall, extending inwardly 50 therefrom and provided with two parallel guide-walls, in the space between which the upper edge of the vessel is received, as set forth.

7. A ventilating-cover having the top A, 55 the wall B, and the base or rim C, said wall having suitable ventilating-openings, and notches E, cut out of the wall at the point of junction with the top A and base C, as set forth.

In testimony that I claim the foregoing as 60 my own I have hereto affixed my signature in presence of two witnesses.

JAMES DAVIES.
